CLAIM

The ornamental design for a paint box, as shown and described.

DESCRIPTION

FIG. 1 is a front view of the paint box showing my new design;

FIG. 2 is a back view thereof;

FIG. 3 is a left side view thereof;

FIG. 4 is a right side view thereof;

FIG. 5 is a top view thereof;

FIG. 6 is a bottom view thereof; and

FIG. 7 is a perspective view thereof.

The broken lines shown in the drawings depict portions of the paint box that form no part of the claimed design.
